TELESCOPIC SIGHT EYE PROTECTOR

Frank Jack Marchetti, 16 W 101 Timber Trails Drive,
Elmhurst, Ill. 60126

Filed Sept. 6, 1973, Ser. No. 394,777

Term of patent 14 years

Int. Cl. D16—06

U.S. Cl. D57—1 E

FIG. 1 is a side elevation of a telescopic eye protector showing my new design;

FIG. 2 is a top plan view thereof;

FIG. 3 is an end elevation thereof;

FIG. 4 is an elevation as seen from the opposite end of FIG. 3;

FIG. 5 is a side elevation thereof; and

FIG. 6 is a side elevation as seen from the opposite side of FIG. 5.

The broken lines are shown for illustrative purposes only.

I claim:

The ornamental design for a telescopic sight eye protector, as shown and described.
